Primary Examiner — Jeffrey D Asch*Assistant Examiner* — Tracey J Bell(57) CLAIM

The ornamental design for a jewelry article with clasp, as shown and described.

DESCRIPTION

FIG. 1 is a front view of a jewelry article with clasp showing my new design; and

FIG. 2 is a rear view thereof.

FIG. 3 is an enlarged view of the front view without the environmental subject matter on which the jewelry article with clasp may be used; and,

FIG. 4 is an enlarged view of the rear view without the environmental subject matter on which the jewelry article with clasp may be used.

The broken lines in the drawings depict environmental subject matter and portions of the jewelry article with clasp that form no part of the claimed design.
